DISHWASHER

Alfred H. Haberstump, Detroit, Mich., assignor to
 The Murray Corporation of America, Detroit,
 Mich., a corporation of Delaware

Application August 29, 1941, Serial No. 408,855

3 Claims. (Cl. 299—63)

1

My invention relates to washers and sprayers and particularly to a washer or sprayer employing a reservoir having discs which throw off spaced sheets of water when rotated.

The present invention embodies a tank in the bottom of which a shaft is journaled having a sleeve on which a plurality of discs of predetermined shape are secured. The sleeve is mounted for axial movement on the shaft and suitable mechanism is provided for reciprocating the sleeves and the discs in timed relation to the disc rotation. The bottom portion of the tank forms a reservoir in which water is introduced to a predetermined height controlled by a suitable float mechanism. When the discs are driven in rotation, the water is picked up thereby and centrifugally thrown upwardly at high velocity against articles to be washed. During the rotation of the discs, the discs are moved by the sleeve axially of the shaft at a slow rate in the order of five or six inches per minute for the purpose of distributing the sheets of thrown off water over all of the area within the tank. The discs are spaced apart approximately the length of stroke in reciprocation of the sleeve on the shaft.

The main object of the invention is to provide a plurality of discs on a sleeve which is driven in rotation and slowly reciprocated to produce, when the discs dip into a reservoir of water a predetermined amount, a plurality of sheets of water thrown centrifugally from the peripheries of the discs, which are moved substantially the distance the discs are spaced so as to cover the entire area of the tank.

Other objects and features of novelty of my invention will be specifically pointed out or will become apparent when referring, for a better understanding of my invention, to the following description taken in conjunction with the accompanying drawings, wherein:

Figure 1 is a broken sectional view, in elevation, of a sink cabinet having a dishwashing unit built therein which embodies features of my invention;

Fig. 2 is an enlarged sectional view of the reciprocating mechanism illustrated in Fig. 1, and

Fig. 3 is an enlarged sectional view of the structure illustrated in Fig. 1, taken on the line 3—3 thereof.

While I have illustrated the washing unit built into a sink cabinet, it is to be understood that such an arrangement is shown primarily for the purpose of illustration and that the washing portion of the cabinet may be mounted as a separate

2

unit or may be disposed in combination with elements other than a sink.

I have illustrated a cabinet 10 of conventional form upon which a sink 11 is mounted having a splashboard portion 12, a sump portion 13, and an opening 14, in which the dish washing tank 15 is mounted. The tank comprises a U-shaped stamping 16 and end stampings 17 and 18 which are welded or otherwise secured thereto. It is to be understood that the tank 15 may be a unit stamping drawn from a single sheet of metal. The opening 14 has flanges 19 about the inner peripheral edge, which receives the outwardly extending flange 19 disposed at the top edge of the tank 15. An angularly shaped sealing gasket 21, made of rubber or other suitable material, is secured to the side wall of the opening 14 and the flange 19 for receiving the peripheral edge of a cover panel 22 which is made from two stampings 23 and 24 having flanged edges which are disposed in telescoping relation to each other.

Supporting bosses 26 project from the inside of the walls of the tank 15 to which they are secured. The bosses form a support for one or a plurality of baskets 27 which fit within the cabinet and nest with each other. The bosses 26 are spaced from the bottom of the tank which forms a reservoir below the baskets.

Bearing brackets 28 are mounted on the walls 30 17 and 18 of the tank for supporting a shaft 29 on which a sleeve 31 is mounted. The right-hand end of the shaft 29, as viewed in the figures, is hollow for receiving a rod 32 through which a pin 33 extends in engagement with the walls of 35 the sleeve 31. A slot 34 is provided in the wall of the shaft 29 to permit axial movement of the rod 32 and sleeve 31 relative to the shaft while transmitting the movement of rotation of the shaft to the sleeve 31. A spring 35 urges the 40 sleeve 31 to the left, as viewed in the figures. The sleeve is provided with a plurality of discs 36 of dish-like formation shaped in a predetermined manner to engage and throw off a large amount of water at high velocity. The discs may be 45 stamped from metal or molded as herein illustrated from a moldable resin composition having a hub portion 37 containing a set screw 38 by which the discs are secured to the sleeve.

As illustrated in Fig. 2, the shaft 29 has a pulley 39 secured thereto by a set screw 41. The pulley is cast from suitable material having a projecting arm 42, in the end of which a pin 43 is supported, constructed from anti-friction material.

The rod 32 has a pulley 44 mounted thereon in a suitable bearing 45 for rotation relative to the

shaft. A swash plate 46 is cast with the pulley 44 having such angularity as to provide substantially an inch movement between the pulleys when the pulleys are operated at relative speeds. A collar 47 is secured to the end of the rod 32 by a pin 48 which retains the pulley 44 on the end of the rod. A cap 49 is threaded on the end of the shaft 29 over the rod 32, against suitable packing washers 51, which seals the rod relative to the shaft. A suitable sealing gland 52 is mounted about the shaft 29 within the bearing supporting element 28. A motor 53 is suspended on a pivoted bracket 54, the weight of which maintains a predetermined tension on belts 55 and 56 which drives the pulleys 39 and 44.

The motor shaft 57 has a pulley 58 mounted thereon which is provided with a wide face to permit the belt 56 to travel thereacross. The pulley 58 has a hub portion 59 to which one-half 61 of a pulley 62 is attached. The other one-half 63 of the pulley is secured thereto by a plurality of bolts 64 which adjust the one-half pulley portion 63 toward or from the one-half portion 61 to slightly change the diameter of the resulting pulley 62. This adjustment is desirable since the speed of reciprocation of the sleeve 31 and discs 36 is preferably less than ten inches per minute. A drain valve 65 is secured to the bottom of the tank 15, having a valve part which is operated from a crank arm 67 by a solenoid 68. When the solenoid is de-energized, a spring returns the valve part to open position. A conduit 73 is secured by a band 74 to the bottom of the float can 75, so that the height of the water within the can will equal that within the bottom of the tank 15. A float is supported within the can on the rod 81, by which the depth of the water in the casing may be regulated.

A cold water pipe 85 and a hot water pipe 86 are connected to the valve 84, either of which is controlled by the solenoid within the casing 83. A suitable bracket 89 supports the mixing valve 84 on the outside of the tank 15.

In operation the belts 55 and 56 are driven at slightly different relative speeds. The shaft 29 is driven in rotation by the belt 55 which rotates the sleeve 31 and the rod 32 along therewith. The difference in speeds of operation between the pulleys 39 and 44 causes the swash plate 46 to advance relative to the pin 43, which produces axial movement of the rod 32 and the sleeve 31 a distance substantially equal to the distance between the discs 36. With the proper amount of water within the reservoir in the base of the tank 15, the rotation of the discs will produce sheets of water thrown upwardly centrifugally from the periphery of the discs with material velocity. The discs, and therefore the sheets of water, are slowly reciprocated substantially the distance be-

tween adjacent discs so that all of the area within the tank is covered by the sheets of water produced by the discs.

What I claim is:

1. In a washing or spraying device, a reservoir for a liquid, a horizontally disposed shaft in said reservoir, a plurality of spaced discs secured to said shaft in position to be partially immersed in a liquid when placed in said reservoir to centrifugally throw spaced sheets of liquid from the periphery thereof when the shaft is rotated, and means for moving said shaft axially for moving said sheets a distance substantially equal to the distance between said discs.
- 15 2. In a washing unit having a reservoir in which a predetermined depth of water may be disposed, a horizontally disposed shaft in said reservoir, a plurality of spaced discs secured to said shaft in position to be partially immersed in the water when contained in said reservoir for centrifugally throwing spaced sheets of water from the periphery of the disc when the shaft is rotated, and means for reciprocating said shaft for moving said sheets backwardly and forwardly a distance substantially equal to the space between said discs.
- 20 3. In a washing or spraying device, a tank, a shaft horizontally mounted in said tank, discs secured on said shaft in spaced relation to each other, means for rotating said shaft and discs, and means for reciprocating said shaft during said rotation.

ALFRED H. HABERSTUMP.
